UNITED STATES PATENT OFFICE.

WILLIAM R. HAVENS, OF DENVER, COLORADO.

LETTER OR PAPER FILE.

SPECIFICATION forming part of Letters Patent No. 295,391, dated March 18, 1884.

Application filed January 15, 1884. (No model.)

To all whom it may concern:

Be it known that I, WILLIAM R. HAVENS, of Denver, Colorado, have invented a new and useful Improvement in Letter and Paper Files, of which the following is a full, clear, and exact description, reference being had to the accompanying drawings, making a part of this specification, in which—

Figure 1 is a vertical section through the file. Fig. 2 is a front view of file with door open. Fig. 3 is a cross-section showing wheel-frame. Fig. 4 is a perspective view of one drawer in detail. Fig. 5 is the drawer detached from the file. Fig. 6 shows the file applied to a desk.

Referring more particularly to the drawings, it will be observed that the file consists of a suitable box or case, A, of any desired size. For ordinary office use a case thirty-six inches high, thirty-two inches long, and twenty inches wide is generally considered sufficient for the reception of current papers, letters, &c.; or the casing may be a part of a desk or table.

Inside of the case I place a vertical wheel revolving on journals i. This wheel is made of two circular pieces of wood fastened to the two ends of the center block, b. Near the outer edges of the disks are placed round pieces of wood c, extending from one disk to the other, with the ends fastened to the two disks. A spring, f, is secured to each stick or round c. These springs are preferably made of brass wire of suitable size, the ends being secured to the pieces c, so that when the spring is raised, by pushing in the tray B it will not slip on the piece c. Each tray B, of which there may be any suitable number, is preferably made of wood; but tin or paper may be used. A flap, h, of heavy paper or other suitable material, is glued or secured to the back edge of the bottom n. The sides of the wheel, or its inner faces, have supporting ledges or bracket-pieces d, the exterior edges of which have the shoulders or stops e. The trays or drawers rest upon these supports d.

In operation, the papers, letters, &c., are laid on the bottom n of the trays. The flaps h are then folded over them, and the tray slipped into position on the supports d, as shown in Fig. 4, the front h' of the drawer resting against the shoulder e. This prevents the tray slipping out or falling when the wheel is revolved. Before the trays are

slipped in, the springs f are in the position 55 shown in Fig. 1; but as the tray is pushed in it strikes said spring and raises it up, and the tray slides on until it strikes the center piece, b, and drops into the shouldered part e of support d. The spring, now being under 60 tension, presses the flaps h down, and serves not only to keep the papers flat, but also holds the tray down behind the stop e. I preferably have twenty - eight trays in the 65 wheel, one for each letter of the alphabet—one for miscellaneous papers, one for bills, receipts, &c.

The trays are lettered on the end next the hinged door m, and there may be corresponding letters on the disks. The trays are removed by raising them so as to clear stop e, and then sliding them out.

It is not necessary that the tray-receptacle be circular, as it may be square or rectangular, there being left sufficient space between 75 the sides of the case for it to revolve in the bearings i.

Having thus described my invention, what I claim as new, and desire to secure by Letters Patent, is—

1. In a paper and letter file, the combination, with a vertically - revolving wheel entirely inclosed within a frame, A, of the trays B, provided with the flaps h, which are held in position by the springs f, secured to the 85 connecting - rods c, the said rods being secured to each of the tray-supports d, having a shoulder, e, against which each of the trays abuts, substantially as and for the purpose set forth.

2. In a paper and letter file, the frame A, adapted to inclose a vertically-revolving wheel provided with a series of trays, B, arranged in guides formed by the supports d, having the shoulders e, in combination with the connecting-pieces c, provided with the springs f, and a flap secured to the tray B, substantially as and for the purpose set forth.

3. In a paper and letter file, a vertically-revolving wheel or tray receptacle provided 100 on its inner faces with a series of tray-supports, d, having shoulders e, as and for the purpose set forth.

WM. R. HAVENS.
